ATTORNEY

UNITED STATES PATENT OFFICE.

THOMAS MILLEN, OF NEW YORK, N. Y.

DESIGN FOR A HOOD-REFLECTOR FOR STREET-CAR SIGNS.

SPECIFICATION forming part of Design No. 30,058, dated January 24, 1899.

Application filed December 2, 1898. Serial No. 698,120. Term of patent 14 years.

To all whom it may concern:

Be it known that I, THOMAS MILLEN, a citizen of the United States, residing at New York city, in the county of New York and State of New York, have invented and produced a new and original Design for Hood-Reflectors for Signs, of which the following is a specification, reference being had to the accompanying drawing, which forms a part of this specification.

My invention relates to the design shown in the accompanying drawing.

The essential feature of my design consists of a sheet-piece extending vertically for a short distance, then rounding over at rectangle, and extending forward horizontally for a distance about equal to that of its vertical portion. The front end of the horizontal portion is curved downward semicircularly, the front of the semicircular portion being

lower than the plane of the horizontal portion. The end pieces, which support the semicircular front portion, extend from the front of the semicircular portion to the point where the said semicircular portion intersects the horizontal portion.

Having thus described my invention, what I claim, and desire to secure by Letters Patent of the United States, is—

The design for a hood-reflector for street-car signs, substantially as herein shown and described.

In testimony that I claim the foregoing invention I have hereunto set my hand this 17th day of November, 1898.

THOMAS MILLEN.
